CLAIM

The ornamental design for a sample container, as shown and described.

DESCRIPTION

FIG. 1 is a front top perspective view of a sample container, showing our new design;

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines are included for the purpose of illustrating portions of the sample container that form no part of the claimed design.
